UNITED STATES PATENT OFFICE.

LOUIS MICK, OF TILLEUR-LEZ-LIEGE, BELGIUM, ASSIGNOR TO SOCIÉTÉ ANONYME DES ACIERIES D'ANGLEUR, OF TILLEUR, NEAR LIEGE, BELGIUM, A CORPORATION OF BELGIUM.

METAL RAILWAY OR LIKE SLEEPER AND RAIL ATTACHMENT THERETO.

Application filed November 2, 1922. Serial No. 598,681.

To all whom it may concern:

Be it known that I, LOUIS MICK, a subject of the King of the Belgians, residing at Tilleur-lez-Liege, Belgium, have invented certain new and useful Improvements in Metal Railway or like Sleepers and Rail Attachments Thereto, of which the following is a specification, reference being had therein to the accompanying drawing.

10 This invention relates to railroad ties and has for its object to provide an improved railroad tie of metal and simplified devices for attaching the rail thereto, characterized by the complete absence of the necessity for 15 any holes or perforations in the metal tie or in the supporting plate or chair, and also by the absence of bolts, spikes or the like, for effecting the connection of the rail to the sleeper. The invention has also for object 20 to construct the supporting plate or chair in two parts, in order to permit an assembly which is rapid, economical and possessed of the required conditions of solidity and security.

25 The invention consists in the construction and combination of parts, as hereafter described, by way of example, with reference to the accompanying drawings in which:—

Figure 1 represents a section of the rail, 30 the tie and the devices for fastening the rail upon the tie, the section being taken on line A—B, Figure 3.

Figure 2 is a cross section of the tie on line C—D, Figure 1.

35 Figure 3 shows a part view in plan of the rail and tie, as well as the fastening devices.

Figure 4 is a part sectional elevation lengthwise of the tie, on line E—F, Figure 5, showing only a single rail fixed to the tie.

40 Figure 5 is a part view in plan of the extremities of the tie upon which only a single rail is fixed.

45 Referring to these figures, the metal tie 1 of inverted U or like section includes two or more longitudinal walls or ribs 7 formed upon its upper face and spaced one from the other in such a way as to form between them a space or gap 9 of suitable width, as will be hereafter described. The middle portion of 50 the tie is provided with a longitudinal

groove or trough 8 extending approximately the full length of the tie.

These walls or ribs 7 are discontinuous at the rail seats, ending at these points in undercut faces 11.

55 The supporting chair plates comprise on the one hand wings or lugs 12 and 13 partly covering the edges of the upper face of the base or flat bottom of the rail 5 and on the other hand projections 6 forming at their 60 middle portions tenons which fit in the space 9 of the tie 1 and engage at their extremities 10 which are of dovetail section, under the extremities or beaks 11 of the walls or ribs 7, correspondingly undercut or 65 profiled as above set forth.

Lastly a retaining device such as a key 4 of suitable cross section, preferably tapering, is engaged in the space formed between the 70 edge of the rail base and the corresponding similarly tapered face of the gap formed by the wing or lug 12 of the supporting chair 2, overhanging the base of the rail 5.

Between the supporting chair-plates 2 and 75 3 there is left a space 15.

From the foregoing description it will be understood that the assembly is effected as follows. Upon the tie 1 there is placed at the assembly point a chair-plate 2 of which the tenon 6 is engaged in the space 9, and the 80 edges 10 under the correspondingly profiled faces 11 of the walls or ribs 7, this engagement being produced by a movement imparted to the plate 2 in the longitudinal direction of the tie. The chair-plate 3 can 85

be placed in position in like manner, because when the assembly is effected, see Figure 1, a clearance space 15 exists between the internal edges of the plates 2 and 3. The rail can then be introduced perpendicularly to 90 the tie, the edges of the base engaging under the parts 12 and 13 of the chair-plates 2 and 3, and the key or retainer 4 afterwards inserted in place. After this key has been 95 introduced and suitably driven into position, as shown in Figure 4, the end 14 of the key 4 is slightly bent up as shown in Figure 3, to prevent it being dislodged. It will be observed from Figure 1 that the overhanging lug 12 of the chair plate 2 is high enough 100

with respect to the lug 13 of plate 3 to permit the rail to be placed in the chair plates without the necessity of canting said rail. In this construction the rail may be lowered 5 in upright, or uncanted, position until the upper edge of the base flange is in alignment with the under side of lug 12; then the rail may be moved horizontally until the right hand edge, looking at Fig. 1, of its base 10 flange clears lug 13; the rail may then be lowered until it rests upon the plates 2 and 3 and finally moved horizontally to the right into the position shown in this view. Another way of placing the rail in the chair 15 plates without canting the rail is to place both plates 2 and 3 in inclined position so that the space between the lugs 12 and 13 is wider than the base flange of the rail, whereupon the rail may be lowered between the 20 lugs and then the whole lowered to horizontal position, the lugs closing in over the edges of the base flange.

As wear or slack takes place at the key, it is taken up by again driving in the key 25 and correspondingly bending up the part 14.

This last operation can be easily effected by a lever or any other suitable instrument.

It follows from the above description that the tie with its connection to the rail, forms 30 a rigid whole, advantageously resisting transverse, longitudinal and upward strains on the rail. By reason of the wedging of the rail in the lugs 12 and 13 of the chair-plates 2 and 3, these latter tend to separate 35 and this causes a tightening of the faces 10 and 11 preventing transverse movements of the rail; relative longitudinal movements between the rail and the chair-plates 2 and 3 are prevented by the tenons 6 engaged in 40 the gap 9 in the tie.

The lifting of the rail resulting from an upward pull is prevented by the lugs 12 and 13 of the plates 2 and 3, which being engaged under the faces of the dovetail ends 45 11 of the ribs 7, can yield only if a closing together of the plates 2 and 3 be possible; this, however, cannot take place, the width of the base of the rail and the thickness of 50 the key or retainer 4 preventing those parts 2 and 3 from closing together.

The advantages of the improved arrangement are easily seen from the foregoing. It will be clear that no holes or perforations 55 of any kind are required in any one of the parts, and that there are no bolts, spikes or other devices as hitherto employed, while the rapidity and security of the assembly will be obvious.

Having thus described my invention what 60 I claim is:—

1. In a railroad tie, the combination of spaced ribs extending longitudinally of the upper surface of the tie, chair-plates adapted to rest upon the upper surface of 65 the tie, tenons upon said chair-plates, said

tenons fitting between said ribs, interengaging surfaces upon said ribs and chair-plates maintained in engagement by separation of said chair-plates, and means for securing the rails to said chair-plates, said 70 securing means tending to separate said chair-plates.

2. In a railroad tie, the combination of spaced ribs extending longitudinally of the upper surface of the tie, said ribs being discontinuous at the rail seats, chair-plates adapted to rest upon the upper surface of the tie at the rail seats, tenons upon said chair-plates, said tenons fitting between said ribs, inclined surfaces upon said chair-plates, correspondingly undercut surfaces on said ribs at their ends adjacent the rail seats and means for securing the rails to said chair-plates, said securing means tending to separate said chair-plates and to 80 maintain said inclined surfaces in engagement with said undercut surfaces.

3. In a railroad tie, the combination of spaced ribs extending longitudinally of the upper surface of the tie, said ribs being discontinuous at each of the points of attachment for the rails, chair-plates adapted to rest upon the upper surface of the tie at each of said points of attachment, a tenon upon each of said chair-plates adapted to fit between said ribs, interengaging surfaces upon each chair-plate and the adjacent ends of said ribs, and means for securing a rail to the chair-plates located at each assembly 90 point, said securing means including hooked flanges overhanging the edges of the rail base and a retaining device adapted to be driven between one of said flanges and the corresponding edge of the rail, said interengaging surfaces being maintained in engagement by the separation of the chair-plates produced by the driving of said retaining device.

4. A railroad tie comprising a metal body having a flat top surface, spaced ribs extending longitudinally of said surface, said ribs being discontinuous at the rail seats, the ends of said ribs adjacent to said points being undercut, chairs resting upon said surface, said chairs including separable sections, 110 each having bevelled surfaces on the outer sides thereof, said bevelled surfaces adapted to engage the undercut ends of said ribs, a tenon upon each of said separable sections, said tenons fitting between said ribs, and means for securing the rails to said chairs, said securing means serving to separate the sections of said chairs.

5. A railroad tie comprising an imperforate metal body having a top surface, spaced 125 ribs extending longitudinally upon said surface, said ribs being alined in parallel and discontinuous rows, chair-plates resting upon said surface at the points of discontinuity of said ribs, tenons upon said chair- 130

plates fitting in the spaces between said ribs, interengaging surfaces upon said chair-plates and the adjacent ends of said ribs, and means for securing the rails upon said chair-plates, said securing means tending to maintain said inter-engaging surfaces in engagement.

In testimony whereof I hereunto affix my signature.

LOUIS MICK.
